United States Patent Office.

THEODORE R. TIMBY, OF SARATOGA, NEW YORK.

Design No. 4,622, dated January 31, 1871.

DESIGN FOR A THREAD AND NEEDLE-CASE.

The Schedule referred to in these Letters Patent and making part of the same.

I, THEODORE R. TIMBY, of Saratoga, in the county of Saratoga and State of New York, have invented an Improved Design for Thread and Needle-Cases, of which the following is a specification.

Nature and Objects of the Invention.

My invention relates to a thread and needle-holder made partially under patent issued to me May 3, 1870, having three portions:

First, a lower portion constituting a spool-box, and having a central well for containing small articles.

Second, a middle portion or tray, having a pin and needle-cushion and a space around the same for thimble, &c.

Third, an upper portion, which is a lid.

The design consists in the shape or conformation of the said box and tray, and in the arrangement of numbered thread openings in the sides of the former.

Description of the Accompanying Drawing.

The figure is a perspective view of the three parts of the case detached.

General Description.

The thread and needle-case to which my invention relates, as aforesaid, consists of a box, A, a tray, B, and a lid, C.

The box A has four sides pierced with holes *a*, each

of which is numbered or lettered to indicate the size of the thread which issues thereat.

Occupying each side of the interior of the box is a spindle, *b*, upon which the spools *c* are strung. This spindle is locked in position, but may be removed when necessary.

The interior space *d* of the box may be used for various odds and ends of the work-table—papers of needles, a thimble, bodkin, &c. The upper portion of the central space is occupied by the depression of the tray above.

The tray B sits within the box A, the upper edges of the two being flush or otherwise, and is covered by the lid C.

In the middle of the tray B is a pin-cushion, *e*, which occupies a depressed portion, *f*, which extends downward into the well *d* of the box A.

The top of the lid may have a trade-mark name or the name of the owner.

Claim.

I claim as my invention—

The design for a thread and needle-case, as herein represented and described.

THEODORE R. TIMBY.
